UNITED STATES PATENT OFFICE.

CHARLES E. MALLETT, OF NEW YORK, N. Y., ASSIGNOR TO THE MALLETT COTTON GINNERS COMPRESS COMPANY, OF SAME PLACE.

REVOLVING BOX FOR COTTON-PRESSES.

SPECIFICATION forming part of Letters Patent No. 684,279, dated October 8, 1901.

Application filed October 12, 1900. Serial No. 32,826. (No model.)

To all whom it may concern:

Be it known that I, CHARLES E. MALLETT, a citizen of the United States, residing at New York, in the county and State of New York, 5 have invented certain new and useful Improvements in Revolving Boxes for Cotton-Presses, of which the following is a specification.

This invention relates to improvements in 10 cotton-presses, and particularly to a revolving box for presses of the kind in which the cotton is packed into boxes and then compressed, the operations of packing and compressing being effected alternately. By providing a plurality of boxes—say two—with 15 means for bringing them alternately and in rotation into coöperative relation with the packing and compressing means I am enabled to effect a large increase in output of the 20 press with a considerable economy in time and to dispense with bulky accumulating devices for accumulating the cotton from a continuous source of supply, such as gins. Even with such accumulating devices it is difficult 25 with the single box to keep a press of proper size for producing the standard bale up to the capacity of the usual gin plant; but by means of my improved box-shifting mechanism the capacity of the press is sufficiently increased 30 to enable it to continuously absorb the product of the gins, the operation of packing the cotton from the gins into one box proceeding concurrently with the compression and tying operations at the other box.

I have herein shown as exemplifying my 35 invention its application to a press of the form disclosed in my Patent No. 661,349, dated November 6, 1900, wherein the cotton from the gins is first compressed into a cohesive 40 bat, which is then folded by feeding means between a platen and a reciprocating plunger, the plunger acting alternately with the feeding means to press the cotton into a box and the platen being pressed back by the 45 pressure of the cotton. As in said application, the cotton is folded by gravity and is retained in place by finger-frames operating after each stroke of the plunger. In the present application I have shown only sufficient 50 of these various means to enable the full illustration of my present invention, which

relates to means for removing the box from the packing devices above referred to as soon as it is full and bringing it opposite a compression means which in this case is separate 55 from the normal pressure-applying means, and not, as in above application, identical therewith.

In the accompanying drawings, Figure 1 is a partly-sectional plan view of a cotton-press 60 provided with my invention. Figs. 1^a and 1^b are details thereof. Fig. 2 is a side elevation. Fig. 3 is a transverse section on the line x x in Fig. 2, and Fig. 4 is a side elevation of the parts shown in Fig. 3. Fig. 5 shows a 65 modification.

Referring to Figs. 1 and 2, the machine comprises a frame composed of longitudinal bars 1, preferably horizontal, and end frames or head and foot standards 2 2'. A plunger 70 3 is arranged to slide on suitable guides—say bars 1—and is operated by links 4 and cranks 5 from the main shaft 6, which is connected by gearing 7' 7" and clutch 10 to the driving-shaft 11. The cotton bat or web passes 75 from suitable bat forming and feeding means through feed-rolls 12, which operate to feed the bat in folds in front of the plunger, this mechanism being fully described in my other application above referred to, but being not 80 herein shown in detail, as it forms specifically no part of my present invention.

Mounted on trunnion-shafts 13, preferably 85 horizontal, journaled in bearings or supports 14 on frame-bars 1, is a rotative frame or carrier 15, which carries a plurality of boxes 16 to receive the cotton, there being two such boxes here shown. The end walls of these boxes can be rigid with rotative frame or carrier 15; but the side walls 16^a, which are 90 longer and are normally at top and bottom of the box, are hinged or pivoted to the frame 15, as shown at 17, so that they can be opened outwardly, to permit the compressed bale to be tied. When said hinged sides are closed, 95 they can be locked by sliding bolts 20 engaging with hasps 21 on cross-frames 22 of the boxes. Within the boxes 16 travel the platens 18, guided by lugs 19 on ends thereof sliding in guideways 23 in the ends of the 100 boxes. The platens 18 are attached, respectively, to the head of a cylinder 8 and to a

- piston or plunger 9 working within said cylinder, the piston 9 and cylinder 8 being located within the frame 15, which is hollow, but not in contact with such frame. When 5 either platen 18 is at the end of the box nearest the axis of rotation of the revolving frame 1, its back rests against a shoulder, ledge, or support 15^a, formed on said frame on each side, so as to give a rigid support. Means 10 are provided for applying pressure within the cylinder 8. For example, a pipe 24, leading from a source of fluid-pressure, connects through rotative coupling 25 with a bore or duct 26 through one of the trunnions, from 15 which it passes by rotative coupling 27, flexible hose 28, and pipe 29 to the interior of cylinder 8. The source of fluid-pressure is such as to always maintain a definite uniform pressure within the cylinder when the press 20 is in operation, while allowing either the cylinder or the piston to move backward under the pressure of the cotton as it is being packed, or to move forward again when such pressure is removed.
- 25 Sliding frames or combs 31 are adapted to work in and out of the box as the cotton is being packed therein, so as to retain the cotton while the plunger 3 is removed from same, it being understood that said plunger has to 30 enter the box sufficiently at each stroke to relieve the pressure from these finger-frames. The operation of these devices is substantially as specified in the application above referred to, being effected through links 31^a, 31^b, and levers 39 from cams on the main shaft, one of which is shown at 33^a; but in this case the support for the said finger-frames is not mounted as a part of the box, but is separate therefrom, so as to permit of 35 its being withdrawn from the box to be swung over on its trunnions. To this end I support the finger-frames 31 on a frame 32, supported on frame-bars 1 by shoulders 33 on said frames 32 engaging over said bars 1, so that frames 32 can slide longitudinally and embrace the ends of the box which is in line therewith or can be withdrawn from the box. This movement of frame 32 is effected by toggle-levers 34, pivoted at one end to head-block 2 and at 40 the other end to said frame and having a handle 35 for the same and a rock-shaft 34^a connecting the toggle-levers on opposite sides of the machine. The finger-frames 31 are detachably connected at 38 to the operating devices, consisting of levers 39 and 40, operated by cams on the main shaft 6, as described and shown in the patent above referred to, these devices forming no part of my present invention.
- 45 50 55 60 65 65
- The pressure-plate 42 on the plunger 3 is detachably secured or locked to said plunger by hooks or bails 43 on the plunger engaging over lugs 44, these lugs sliding in the guide-ways 23 in the ends of the box when the plunger is fully advanced at each end of the pressure-plate. Similar hooks or bails 45 on the ends of each box enable the pressure-plate to

be secured or locked to the box, so that by throwing off the plunger-hooks 43 and engaging the box-hooks 45 the pressure-plate may 70 be detached from the plunger and attached to the box and will then serve to hold the cotton in place in the box while the box is swinging around on the trunnions.

The reversal of the rotating frame or carrier is effected by gearing consisting of a gear 47 on one of the trunnions thereof engaged by a pinion 48 driven from the main driving-pulley 49 through friction-clutch connection 50 and gears 51 51'. As the said frame comes 80 around to proper position it is stopped and locked by throwing off the clutch and inserting a peg 52 through one of two holes 53 in gear 47 and into a hole 54 in the frame or standard 2", thus arresting the boxes in ex- 85 act alinement with the packing-plunger at one end and with the compressing-plunger at the other end of the machine.

When the box is swung around to the rear end of the press, it comes opposite a compression plunger or platen 57, attached to the heads of cylinders 58, whose pistons 59 are attached to the foot-frame 2'. A supply-pipe 60 admits fluid-pressure to cylinders 48, so as to drive the platen 57 into the box.

Dogs 61 are arranged at the inner corners of each box to retain the platen 18 in innermost position when said dogs are thrown in.

When the press is started in operation, both boxes are empty, and the dogs 61 are therefore thrown in back of the platen in the rear box to afford a support for the cylinder and piston means 8 9, connecting the two inside platens. Then on admitting pressure to cylinder 8 the platen in the front box—that is, the one nearest the plunger—is forced forward until it reaches the front of the box a little back of the fingers. This forward movement of the platen is effected by forward movement of the cylinder 8 or of the piston 9, according to which of these parts is presented toward the plunger 3, the other of such parts being at this time held from back movement, so as to act as an abutment by the dogs 61. The usual requirements as to bagging having been attended to, the press is started, and the feeding means and packing-plunger operate to pack the front box full of cotton in compact layers. This box having been filled, the packing and feeding means are stopped 120 for a moment by clutch 10. The tie-plate is uncoupled from plunger 3 and hooked to the box 16. The handle 35 is thrown over to withdraw frame 32 from the front box. Dogs 61 are released, and the box-rotating mechanism is set in action by clutch 50, so as to carry the filled box to the rear, at the same time bringing the other box to the front ready for filling. The carrier 15 is stopped by uncoupling its clutch and inserting the peg 52. The operator then unhooks the outer platen from the empty box and hooks it to the plunger, throws handle 35 back to push frame 32 over the end of the empty box 42, and then clutch

10 is thrown in again to start the packing of the new box. At the same time another operator is attending to the compression at the other end of the press by admitting pressure 5 to cylinders 58, so as to force the outer platen of the filled box inward, and then opening the hinged sides 16^a of the box and tying up the compressed bale in the usual manner, the operations of packing at the front and compressing and tying at the rear box taking place concurrently, and the above-described operations being repeated in rotation as each front box is filled, except that dogs 61 are not used again as long as the press is in regular operation.

15 It will be noted that in the above-described construction the pressures of the packing-plunger and of the compressing means are exerted substantially in alinement, so that 20 there is no tendency of these two pressures acting simultaneously to twist the frame, the said pressures being received directly by the trunnions or axis of the revolving carrier, which is located between the packing and 25 the compressing means, and in case there is an excess of pressure one way or the other it is transmitted to the trunnions and the frame in the direction of greatest strength of the machine—namely, longitudinally of the frame of 30 the machine. While desirable, however, this feature may be departed from; but in any case I desire to make the shaft of the revolving carrier horizontal, so as to enable the cotton-bat to be folded by gravity, as above described, and to be packed into the box by a 35 horizontally-acting plunger.

In Fig. 4 I show as an example a modification with the trunnions horizontal, but extending longitudinally of the machine, so 40 that the carrier moves transversely of the machine. The compressing-cylinders 58 are in this case off at one side, supported by an extension of the rear head-frame 2 and the pressure exerted upon the front platen, when the 45 compress is acting, being taken by a supplementary front head 2^a. The piston 9 for the packing-cylinder 8 is supported directly on the rear head-frame 2'. In other respects the construction will be the same as in Figs. 1 50 and 2.

Having thus described my invention, the following is what I claim as new therein and desire to secure by Letters Patent:

1. In a cotton-press, the combination with 55 the feeding means, packing-plunger and compression-plunger, and means for operating said parts, of a device carrying boxes and movable to bring such boxes alternately in cooperative relation with the two plungers afore- 60 said and pressure-plates for each box with

means for locking same to the packing-plunger, and means for locking said pressure-plates to the boxes.

2. In a cotton-press, the combination with 65 the feeding means, of the packing-plunger and compression-plunger reciprocating in substantial alinement and means for operating said parts, a device carrying boxes and movable to bring such boxes alternately in cooperative relation with the two plungers afore- 70 said, platens mounted inside the boxes and means mounted on said carrying device for applying pressure to such platens when coöperating with the packing-plunger.

3. In a cotton-press, the combination with 75 the feeding means, of the packing-plunger and compression-plunger reciprocating in substantial alinement and means for operating said parts, a carrier, carrying boxes and movable to bring such boxes alternately in cooperative relation with the two plungers afore- 80 said, platens mounted inside the boxes and a cylinder and piston device mounted on the carrier for applying pressure to such platens when coöperating with the packing-plunger. 85

4. In a cotton-press the combination with 90 the feeding means, of the packing-plunger and compression-plunger, reciprocating in substantial alinement, and means for operating said parts, a carrier, carrying a plurality of 95 boxes and adapted to bring same in rotation in cooperative relation with the packing and compressing plungers, and a cylinder and piston device, supported by said carrier with platens mounted respectively on the cylinder and the piston, and traveling within the boxes.

5. In a cotton-press, the combination with 100 the packing-plunger, the platens, and a rotating carrier for said platens, wherein the platens are longitudinally movable, of means for supporting said platens against the action of the plunger, comprising dogs which are supported on the rotating carrier and are adapted to engage with the platens to positively 105 hold the platens from back movement, said dogs being movable out of such engagement so as to be thrown out of action.

6. In a cotton-press, the combination with 110 the feeding and packing means, of a box movable into and out of cooperative relation with such feeding and packing means, retaining-finger frames for retaining the cotton in the box and a support for same movable into and out of engaging relation with the box.

CHARLES E. MALLETT.
